UNITED STATES PATENT OFFICE.

WILLIAM HUTTIG, SR., AND NICKLAS BAST, OF MUSCATINE, IOWA.

DESIGN FOR A SASH-FASTENER.

SPECIFICATION forming part of Design No. 16,507, dated February 9, 1886.

Application filed December 29, 1885. Serial No. 187,071. Term of patent 7 years.

To all whom it may concern:

Be it known that we, WILLIAM HUTTIG, Sr., and NICKLAS BAST, both of Muscatine, in the county of Muscatine and State of Iowa, have invented and produced a new and original Design for a Window-Sash Fastener, of which the following is a full, clear, and exact description.

Our new design for a window-sash fastener 10 consists in a novel configuration of the fastener, mainly as seen from its side, substantially as shown in the drawing, and herein-after described.

Reference is to be had to the accompanying 15 drawing, forming part of this specification, in which the figure represents a view in perspective of a window-sash fastener having our new design.

The fastener, as seen from its side, presents 20 generally a flat appearance, with a head portion, *b*, and tail portion *d*, the marginal contour of which is mainly made up of a series of curved lines. The head portion *b* is of circular marginal configuration, ornamented by 25 angularly-shaped projections *c* on its circular outline, and by a circular aperture, *e*, in its face eccentric to the circular outline of the head. The tail portion *d* is of approximately straight outline along its one or outer edge, *f*,

from the point where it joins the circular outline of the head to a point near its outer end, from which latter point it is of convex configuration for the remainder of its length. This edge or marginal portion *f* of the tail *d* is ornamented intermediately of its length by 35 a leg-like projection, *g*, at right angles, or there-about, to the straight marginal portion of the tail. The opposite edge or marginal portion *h* of the tail is of concave outline, and forms an easy or gradual curved junction with the 40 circular outline of the head, making the tail to present a tapering appearance on its face or side, beginning with the head.

We claim—

The design for a window-sash fastener 45 herein shown and described, the same consisting in part of the head *b*, of circular outline, ornamented by angular projections *c* and an eccentric aperture or eye, *e*, and in part of a tail, *d*, of tapering width, and of approximately 50 straight and curved outlines, with a leg-like projection, *g*, on its outer or straight marginal portion.

WILLIAM HUTTIG, SR.
NICKLAS BAST.
